EYE OPENING AND CLOSING MECHANISM
FOR DOLLS

William N. Wheeler, Lexington, Ky.

Application December 27, 1941, Serial No. 424,623

3 Claims. (Cl. 46—166)

My invention relates to eye opening and closing mechanisms for dolls and of the type operative to effect closing of the eyes under rocking of the doll, as exemplified in my copending application, Serial No. 406,708, filed August 13, 1941, over which the instant invention is designed as an improvement.

The principal object of the instant invention is to provide, as compared with prior devices, a more simplified eye opening and closing mechanism operative to close the eyes after the doll has been rocked for a while, and which is proof against sticking.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a fragmentary view in vertical section of a doll's head equipped according to the preferred embodiment of my invention, the parts being shown in eye opening position as when the doll's head is held in upright position.

Figure 2 is a similar view showing the parts in eye closing position, as when the doll's head is held in reclining position.

Figure 3 is a view in front elevation of the mechanism detached and drawn to an enlarged scale,

Figure 4 is a view in transverse section taken on the line 4—4 of Figure 3, and

Figure 5 is a detail view in section taken on the line 5—5 of Figure 3.

Referring to the drawings by numerals, according to my invention, the head 1 of a doll is provided above the eyes 1' with slots, as at 2, for the projection of eyelid members therethrough into eye closing position.

A bracket plate 3 is attached in the head 1 to the back thereof in any suitable manner, for instance, as indicated at 4, to be disposed in upright position in the upright position of the doll. The plate 3 embodies a pair of upper bracket arms 5 extending forwardly from opposite side edges thereof in laterally spaced relation and in which are journaled the opposite ends of a rock shaft 6 extending lengthwise between the sides of the head 1. Extending upwardly from the longitudinal center of the rock shaft 6, in the upright position of the doll, is a T-shaped, rod-like lid carrying member 7 on which are suitably fastened eyelid members 8 adapted to be projected

out of the slots 2 into eye closing position and retracted into eye opening position under rocking of the rock shaft in opposite directions. Depending from the center of the rock shaft 6 is a rod-like weight carrying member 9 having its lower end suitably fixed in a segmental flat-sided weight 10. As will presently more clearly appear, the weight 10 is designed, when the doll is tilted into reclining position and rocked back and forth endwise, to be oscillated in the median plane of the doll back and forth to cause the rock shaft to project and retract the eyelid members 8. A third and lower bracket arm 11 extends forwardly from the plate 3 alongside the weight 10 and is spaced laterally from said weight. The bracket arm 11 has a right angled upper edge flange 12 of plate-like form shorter than the arm and providing at its rear end a stop 13. A lateral stop forming extension 14 is provided on the rear end of the weight 10 to abut the stop 13 in the upright position of the doll and establish a limit of movement of said weight 10 in one direction, in which limit the eyelid members 8 are held retracted into eye opening position.

The weight 10 carries a vertically swingable locking member having a right angled rear end 15 rotatably extended through the rear end of the weight 10 and through the extension 14 parallel with the axis of the rock shaft 6, said member also comprising a shank 16 extending forwardly alongside the weight 10 and having a downturned arcuate front end 17 which, in the described limit of movement of the weight 10, hooks over a transverse lock releasing shaft 18 journaled in the front end of the bracket arm 11 and in a right angled downturned extension 19 of the flange 12. The releasing shaft 18 extends parallel with the shaft 6. Also, the releasing shaft 18 is offset downwardly from the front end of the flange 12 and said front end is inclined to the shaft 18, as at 20, for a purpose presently seen. At one end thereof, the releasing shaft 18 is formed with an angularly related extension 21 carrying a terminal weight 22, whereby when the doll is tilted into reclining position and rocked back and forth endwise, the weight 22 may be oscillated to rock the lock releasing shaft 18. A right angled stop forming end 23 on said releasing shaft 18 is interposed between a pair of stop lugs 24, 25 provided on the front end of the extension 19 for alternate engagement by said end 23 to limit rocking movement of said releasing shaft 18 in opposite directions.

Referring now to the operation of the mechanism, when the doll is tilted and rocked in re-

clining position, the weight 22 is oscillated with the arcuate end 17 of the locking member in frictional engagement with the releasing shaft 18 whereby said end 17 is oscillated crosswise of the shaft 18. However, the arcuate end 17 is eccentric to its axis of swinging movement in the weight 10, being formed in an arc the center of which is forwardly of the axis of the right angled end 15 of the member, that is in the reclining position of the doll. The result of this arrangement is that said arcuate end 17 under oscillation thereof gradually slides off the releasing shaft 18 and permits this weight 10 under the influence of gravity to swing away from the flange 12 and in a direction to cause the eyelid members 8 to suddenly close. As said arcuate end 17 slides off the shaft 18, the eyelid members 8 close and the weight 10 abuts the stop lug 26 on the plate 1. During such closing of the eyelid members 8, the arcuate end 17 slides down the flange 12. Under tilting of the doll into upright position, the weight 10 swings under the influence of gravity in the opposite direction toward the flange 12, in which direction of movement of said weight the eyelid members 8 are caused to open and said arcuate end 17 to slide along the flange 12 and over the releasing shaft 18, at which point it drops over said shaft. The inclined front end 20 of the flange 12 guides the arcuate end 17 of the locking member over said shaft 18. As will be understood, under swinging of the weight 10 in said opposite direction, the stop forming extension 14 engages the stop end 13 of the flange 12 and the arcuate end 17 of the locking member slightly clears the releasing shaft 18 so that it may drop over the same. A lateral stop pin 27 on the weight 10 is provided for engaging the shank 16 of the locking member to limit swinging movement of the locking member away from the flange 12 if the doll is tilted upside down and for a purpose which will be obvious.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the subjoined claims.

What I claim is:

1. In a doll including a head, and eyes in said head, eye closing mechanism including a pair of lid members operative into eye closing position, means to operate said members comprising a weight pivotally mounted in said head for swinging movement under the influence of gravity when the doll is held in reclining position to

move said members into said closing position, and means to releasably lock said weight against such swinging in the reclining position of the doll comprising a second weight swingable in said head in opposite directions under rocking of the doll endwise in the reclining position thereof, and coengaging devices disengageable gradually under such swinging of said second weight, said devices comprising a rock shaft operative in opposite directions under such swinging of said second weight, and a member pivoted on said first-mentioned weight and slidably engaging said shaft.

2. In a doll including a head, and eyes in said head, eye closing mechanism including a pair of lid members operative into eye closing position, means to operate said members comprising a weight pivotally mounted in said head for swinging movement under the influence of gravity when the doll is held in reclining position to move said members into said closing position, and means to releasably lock said weight against such swinging in the reclining position of the doll comprising a second weight swingable in said head in opposite directions under rocking of the doll endwise in the reclining position thereof, and coengaging devices disengageable gradually under such swinging of said second weight, said devices comprising a rock shaft operative in opposite directions under such swinging of said second weight, and a member pivoted on said first-mentioned weight and slidably engaging said shaft, said member comprising an arcuate shaft engaging part eccentric to the pivotal axis of the member.

3. In a doll including a head, and eyes in said head, eye closing mechanism including a pair of lid members operative into eye closing position, means to operate said members comprising a weight pivotally mounted in said head for swinging movement under the influence of gravity when the doll is held in reclining position to move said members into said closing position, and means to releasably lock said weight against such swinging in the reclining position of the doll comprising a second weight swingable in said head in opposite directions under rocking of the doll endwise in the reclining position thereof, and coengaging devices disengageable gradually under such swinging of said second weight, said devices comprising a rock shaft operative in opposite directions under such swinging of said second weight, and a member pivoted on the first-mentioned weight and slidably engaging said shaft, said member comprising an arcuate shaft engaging part eccentric to the pivotal axis of the member, and hooking over said shaft.

WILLIAM N. WHEELER.
